Inventor

John P. Hayes

UNITED STATES PATENT OFFICE.

JOHN P. HAYES, OF PHILADELPHIA, PENNSYLVANIA.

OVEN.

Specification of Letters Patent No. 16,143, dated December 2, 1856.

To all whom it may concern:

Be it known that I, JOHN P. HAYES, of the city of Philadelphia, in the State of Pennsylvania, have invented a new and 5 useful Improvement in Ovens; and I do hereby declare that the following is a full, clear, and exact description of the construction and operation of the same, reference being had to the accompanying drawings, 10 making a part of this specification, in which—

Figure 1, is a transverse vertical section; Fig. 2, a longitudinal vertical section; Fig. 3, a horizontal section just below the top 15 plate; and Fig. 4, a like section just above the lower oven; similar letters on the different figures, indicating the same objects.

My invention relates to those cast-iron ovens which are usually constructed and 20 applied as "elevated side ovens" in connection with a "range" for generating the heat, and consists in a peculiar mode of constructing and arranging the draft flues and escape, so as to diffuse the heat more equably 25 around the ovens, and especially so over the top of the same.

Referring to the drawings A, A', are the ovens proper; B, B, the outer casing; C—C⁹ the flues, the direction of the draft of which, 30 being indicated by the arrows; D, the escape; and E, the damper. The ovens are both made to draw out of the casing (B), in the usual manner, for the purpose of cleansing the flues, the two sides, top, and back of 35 the said ovens being made of sheet-iron united together, and the sides sliding in grooves in the stationary cast iron plate which forms the bottom of each oven—the usual doors when closed, constituting the 40 front. It has hitherto been the practice to make a "dumb flue" space behind each of these ovens as well as at one side, and consequently the direct draft or strongest heat in such constructions passes first be- 45 beneath the oven, then up one side, and finally over the top to the escape flue, thereby heating these sides of the oven more intensely than the "dumb flue" sides; and also in conducting the draft to the escape, over the 50 top surface of the upper oven as hitherto, a perfect diffusion of the heat over the said surface, has not been attained. To remedy these defects, I make the vertical partition plate (f) which heretofore produced the 55 "dumb flue" behind the oven, with an oblong opening (g,) through it on the side

next to the oven, which opening is about one fourth the width and nearly the whole length of said plate, as shown in the drawings—or, of such a capacity as will cause 60 the direct draft (C) which enters from the range-fire, to be divided into two currents; the one passing across beneath the oven and up on the side C'; the other, along the opposite side (C²) thence behind the oven 65 (C³), and through the oblong opening (g), where it joins the other current (C'), and then together as one current (C⁴) passes between the ovens (A and A'); or, (if only one oven exists) over the top of the same to 70 the escape flue (D). This perforated partition (f) is fixed to the back of the movable sheet-iron oven-casing, so as to be withdrawn with it; and, for the purpose of 75 catching the soot and ashes which from time to time become deposited on the top of the oven, I fix a trough (h), which, being of the same width as the partition plate (f), its bottom forms the usual top partition plate which prevents the current from passing up- 80 ward, and now directs it to the oblong opening (g); and so that when the oven is being drawn out, the soot and dust on top thereof is heaped up by being drawn in contact with the stationary outer front casing (B) until 85 the trough (h) reaches the same, when the said soot and dust falls thereinto and becomes removed with the oven; thus preventing its deposit upon the lower plate of the oven as hitherto. For the purpose of more 90 equably diffusing the heated current, over the top of the upper oven, or the one next to the escape, I make the said escape flue (D), directly over the center of the same, and shut off the draft on three sides of 95 the same, by means of the vertical plates, or partitions (F, F, F), so arranged that as the current which comes up from the flue (C⁷) at the side and passes over the top of the oven, it becomes divided into two cur- 100 rents (C⁸ and C⁹) by the said plates, as shown by the arrows, and passing the plates they again unite into one current (C⁹) and return between the said plates, and thus enter the escape (D); every part of the top 105 of the said oven being thus more equably subjected to the action of the heated draft than by any other arrangement hitherto known or used. The strength or velocity of the heated current or currents, is regulated 110 by means of the damper (E) in the usual manner.

What I claim as my invention and desire to secure by Letters Patent, is as follows, viz:

1. I claim making an oblong opening (g) through the plate (f) which is fixed to the back of each of the ovens, substantially and for the purpose set forth and described.

2. I claim the arrangement of the soot-

catching trough (h) at the back part of each of the said ovens, substantially and for the purpose set forth and described.

JOHN P. HAYES.
